SWITCH FOR TV CABLE AND ANTENNA

James C. Matthews, 115 Harding Drive,
Washington, N.J. 07882

Filed July 19, 1974, Ser. No. 490,135

Term of patent 14 years

Int. Cl. D13—03

U.S. Cl. D26—13 R

Fig. 1

Fig. 2

Fig. 3

FIG. 1 is a perspective view of a switch for TV cable and antenna depicting the left, front, and top sides thereof, in accordance with this invention;

FIG. 2 is a rear view thereof; and

FIG. 3 is a perspective view thereof depicting the front, right, and bottom sides thereof.

A cable, shown in dotted line format, does not form a part of my novel design.

I claim:

The ornamental design for a switch for TV cable and antenna, as shown and described.
